LOOSE LEAF BINDER

Paul O. Unger, Glen Ellyn, Ill., assignor to
 Wilson-Jones Company, Chicago, Ill., a corpora-
 tion of Massachusetts

Application January 29, 1934, Serial No. 708,757

12 Claims. (Cl. 129—8)

This invention relates to a loose leaf binder which may be expanded to vary the capacity of the binder.

It is an object of this invention to provide a loose leaf binder of variable capacity capable of holding its sheet contents under compression. It is a further object of this invention to provide a loose leaf binder in which the entire contents may be readily removed as a unit and handled without difficulty. It is a further object of this invention to provide a permanent lock for the binder. Other objects of this invention will become apparent upon reading the following description taken in conjunction with the accompanying drawings, in which:

Figure 1 is a top plan view of a loose leaf binder embodying the invention, with parts broken away to facilitate illustration of the structure;

Figure 2 is a view similar to Figure 1, showing the binder open in its outermost position;

Figure 3 is an enlarged fragmentary detail showing one embodiment of the permanent lock mechanism in unlocked position;

Figure 4 is a view similar to Figure 3 showing the permanent lock mechanism in locked position;

Figure 5 is a cross sectional view taken along the line V—V of Figure 1 looking in the direction of the arrows;

Figure 6 is a cross sectional view taken along the line VI—VI of Figure 1 looking in the direction of the arrows;

Figure 7 is a top plan view of another embodiment of the invention, showing the binder in permanently locked position, but with the sheets and sheet retaining prongs removed;

Figure 8 is a fragmentary detail of the permanent locking mechanism of the embodiment illustrated in Figure 7;

Figure 9 is a view similar to Figure 7, showing the binder in unlatched position;

Figure 10 is a cross sectional view, taken along the line X—X of Figure 9, looking in the direction of the arrows;

Figure 11 is a detail view partly in elevation and partly in section, illustrating the means for holding the operating lever in open position; and

Figure 12 is a detail perspective, with parts broken away, illustrating one of the sheet retaining members and its associated binder structure.

In the drawings, the reference numerals 2 and 3 indicate a pair of cover members connected to opposite edges of a pair of compression members 4 and 5. The outer edges of the compression members are bent upwardly, as indicated at 6,

and then downwardly, as indicated at 7, to form a pair of channels in which the inner edges of the cover members 2 and 3 are received. A flanged plate 8 is positioned adjacent each channel, and each plate and cover member is permanently secured to the adjacent channel by means of a plurality of rivets 9, or in any other suitable manner. If desired, a single upstanding wall may be substituted for the double wall 6, 7, and the flanged plate 8 will serve to take the place of the wall 7.

The ends 10 of the top wall of the flanged plate 8 are bent downwardly to close the ends of the space defined by the top wall of the flanged plate, the side wall 6, and the adjacent edge of the compression member 4 or 5. The spaces so formed are adapted to receive a pair of cooperating transfer bars 11 and 12, and the structure defining the spaces is adapted to prevent the bars from moving longitudinally, vertically, or transversely in an outward direction relative to the binder. The ends of the side wall of the flange 8 may be bent forwardly to prevent longitudinal movement of the transfer bars, instead of the ends 10 being bent downwardly.

The transfer bars 11 and 12 are provided with staggered prongs 13 upon which a plurality of sheets 14 may be impaled. The prongs 13 may be secured to the transfer bars in any suitable manner. In the preferred form, the transfer bars are each formed of a metal plate bent to form a bar U-shaped in cross section. The prongs have one end extending through apertures in the bight of the bar and are welded or riveted between the two walls of the transfer bar. As shown in Figures 1 and 6, the prongs are of sufficient length so that when the binder is compressed to its minimum capacity, the free ends of the prongs fit under the top walls of the flanged plates 8. The transfer bars 11 and 12 are provided with recesses 11' and 12', respectively, to receive the free ends of the prongs when the binder is compressed to its minimum position.

This structure prevents the transfer bars from becoming accidentally displaced when the binder has not sufficient sheets to fill it to its minimum capacity. Each transfer bar is provided at its ends with a pair of recesses 15 and intermediate its ends with recesses 16 to provide clearance for various parts of the binder mechanism when the binder is compressed to its innermost position.

The binder is provided with a back member which includes a flat plate member 17 and a rounded back plate 18. The rounded plate 18 is covered with binding material 19 to harmonize

with the appearance of the covers 2 and 3. A pair of tongues 20 struck out from the plate 18 each project through a slot 21 in the flat plate member 17. The plate member 17 is provided 5 with a depressed area 22 adjacent the slot 21 to provide room for the end of the tongue 20 which is bent down against the flat plate member 17. A bridge member 23 is secured between the plate members 17 and 18 to reinforce the structure to 10 prevent the tongue 20 from collapsing. The bridge member 23 straddles the tongue 20 and is provided with a slot 24 registering with the slot 21.

The ends of the back plate 17 are bent upwardly and then over, as indicated at 25, to provide a pair of transverse guide channels adapted 15 to receive the ends of the compression members 4 and 5. A pair of toggle links 26, each having one end secured to a compression member by 20 means of a stud 27, is provided for each compression member 4 and 5. The height of the bent over portion 25 and of the studs 27 is small enough so that these parts may be received in the recesses 15 and 16 respectively when the binder is closed to its innermost position. The ends 25 of the toggle links 26 opposite the studs 27 are each secured to a centralizing bar 28 by means of studs 29.

The centralizing bar 28 is secured to the back 30 plate 17 by means of a plurality of shouldered studs 30, each of which projects through a slot 31. The slots 31 are elongated to permit a limited longitudinal movement of the bar 28 relative to the studs 30. The toggle links 26 connecting the 35 bar 28 with the compression members 4 and 5 cause the bar to move longitudinally whenever the compression members are moved transversely relative to each other. Accordingly, the length of the slots 31 determines the limits of the trans- 40 verse movement of the compression members, and any means preventing longitudinal movement of the centralizing bar would also prevent transverse movement of the compression members. The toggle connections at each end of the centralizing bar cause both ends of each compression member to move simultaneously, so that the back 45 member is always spaced centrally with respect to the compression members.

A cover plate 32 is provided with apertures to 50 fit over the studs 30. The ends of these studs are spun over, as indicated at 33, to secure the cover plate 32 permanently in place over the operating mechanism of the binder. A pair of projections 34 are provided on the upper surface 55 of the bar 28 to space the cover plate from the operating mechanism.

The structure hereinabove described is generic 60 to both embodiments of the invention illustrated in the drawings. The two structures illustrated differ from each other only in the means locking the binder parts against outward transverse movement either temporarily or permanently. The locking mechanism for each embodiment will now be described specifically.

In the embodiment illustrated in Figures 1 to 65, inclusively, the centralizing bar 28 is provided with a plurality of teeth or similar projections 35 on one edge. A pawl or lever 36, pivoted near one end to the plate 17 by means of a stud 37, 70 carries a tooth 38 adapted to engage with the teeth or other projections 35 to prevent longitudinal movement of the bar 28 in one direction to prevent outward transverse movement of the compression members. A spring 39 having one 75 end secured in a notch in the lower end of the

pawl 36 and its other end secured in a similar notch in the shouldered stud 30 is adapted to throw the pawl tooth 38 either into or out of engagement with the teeth 35.

The releasing movement of the pawl tooth 38 is controlled by a slide member 40 having an arm 41 projecting beyond one end of the binder. The member 25 has a pair of projections 42 struck therefrom to facilitate guiding the arm. The outermost end of the arm 41 is bent, as indicated at 43, Figure 5, to provide a finger grip to facilitate manipulation of the arm. The slide member is provided with an elongated slot 44 through which the stud 37 projects, and a slot 45, through which the pawl tooth 38 projects. A portion of the slot 45 is parallel to the slot 44, and a portion is angular with respect thereto.

The operation of the binder is very simple. Figure 1 shows the bonder mechanism in closed position. When the slide member 40 is pulled outwardly to the position shown in Figure 2, the angular portion of the slot 45 engages the pawl tooth 38 and causes it to move away from the teeth 35. As soon as the pawl 36 passes dead center position, the spring 39 throws the pawl 25 to its outermost position. The compression members 4 and 5 may then be moved transversely outwardly so that the sheet contents and transfer bars may be moved as a unit. Inward movement of the slide member 40 moves the pawl 30 into engagement with the teeth 35. In this position the spring 39 and the elongated straight portion of the slot 45 will allow the pawl tooth 38 to be moved outwardly far enough to be disengaged from one tooth but will throw it 35 back into engagement with the next tooth.

The means for permanently locking the binder consists of a tooth-like extension 46 projecting from the upper end of the slide member 40, and a projection 47 secured to the back plate 17. The 40 projection 47 may be welded or riveted to the back plate, or may be struck out from the plate itself. The meeting edges of the members 46 and 47 are beveled, as indicated at 48 and 49, to facilitate passing movement in one direction. 45 Figure 3 shows the permanent locking mechanism in unlocked position. The position of the parts is the same as in Figure 1. The end of the arm 41 adjacent the bent portion 43 is weakened so that the bent portion may be broken off to 50 permit further inward movement of the slide member. When the slide member 40 is moved inwardly beyond the position indicated in Figure 1, the member 46 springs over the projection 47 to effect a permanent locking of the binder 55 parts. Since the cover plate 32 is riveted in place, the parts 46 and 47 are not accessible. The finger portion 43 is broken off so that it is impossible to move the tooth 38 without leaving visible evidences of tampering with the mechanism.

Even after the binder has been permanently locked it is possible to move the compression members inwardly if the sheets will permit additional compression, due to the fact that the elongated portion of slot 45 parallel to slot 44 65 is wide enough to permit outward movement of tooth 38 around one tooth 35 to engage the next tooth.

In the embodiment illustrated in Figures 7 to 11, inclusively, the centralizing bar 28 is provided with a plurality of teeth or other projections 59 along a portion of one edge thereof. A pawl 51 is pivoted to the back plate 17 by means of a stud 52. The pawl carries a tooth 53 at 70 one end. The tooth 53 may be integral with 75

the pawl 51 or may be secured thereto in any suitable manner. The pawl tooth 53 is adapted to engage the teeth 50 to prevent longitudinal movement of the centralizing bar in one direction. A spring 54 is secured to the back member 17 by means of a pair of straps 55 which may be struck out from the plate 17 or may be welded thereto. The spring exerts a constant force against the pawl 51 tending to move the tooth 53 into engagement with the teeth 50.

The lower end of the pawl 51 is provided with a recess 56. An operating lever 57, pivoted to the back plate 17 at 58, is provided with a rounded end 59 smaller than the recess 56 and adapted to be received therein. The portion of the lever near the end of the binder is raised, as indicated at 60, Figure 10, to permit it to clear the toggle link 26. The lever is provided at its free end with a laterally offset handle 61 which projects beyond the end of the binder a distance sufficient to permit manipulation of the lever. A strap 62 is secured to the member 25 to hold the handle 61 in position. The strap 62 is provided with a projection 63 adapted to fit in an aperture 64 in the handle 61 to hold the lever in open position.

When the binder is in unlatched position, as shown in Figure 9, the compression members 4 and 5 may be moved transversely outwardly. Although the spring 54 is pressing against the top edge of the pawl 51, the tooth cannot be moved into engagement with the teeth 50 because the end 59 of the lever 57 will not permit the lower end of the pawl 51 to move outwardly. When the handle 61 is moved to the left, as shown in Figure 7, the spring 54 immediately forces the pawl tooth 53 into engagement with the teeth 50 to temporarily lock the binder against expansion just as in the case of Figure 1.

The means for permanently locking the binder of Figures 7 to 11, inclusive, consists of a plug 65 having a shoulder 66 adapted to abut a shoulder 67 provided on the lever 57 to prevent the plug from being driven too far inwardly. A resilient arm 68, integral with the plug 65, is adapted to spring outwardly as soon as it passes the strap 62 to prevent the plug from being pulled out of locking position. The plug is also provided with an aperture 69, similar to the aperture 64, to receive the projection 63 depending from the strap 62. Once the plug 65 has been inserted in position, as shown in Figures 7 and 8, the lever 57 cannot be moved to the right and, consequently, the compression members 4 and 5 cannot be moved transversely in an outward direction. However, the difference in size between the recess 56 and the end 59 is sufficient to permit the pawl to move sufficiently to have the pawl tooth disengaged from one tooth, but the spring 54 will throw it back into engagement with the next tooth. Accordingly, the compression members may be moved inwardly even after the permanent lock plug is in locking position if the sheet contents will permit such additional compression.

While I have described preferred embodiments of my invention in detail, it will be understood that the description thereof is illustrative rather than restrictive, as many details may be modified or changed without departing from the spirit or scope of my invention. Accordingly, I do not desire to be restricted to the exact construction described, except as limited by the appended claims.

I claim:

1. In a loose leaf binder, a pair of compression

members movable transversely relative to each other, a bar connected to said compression members and movable longitudinally of said binder when said compression members move transversely, and means to permanently lock said compression members against expansion by preventing longitudinal movement of said bar in one direction.

2. In a loose leaf binder, a back member, a pair of compression members movable transversely of said back member, a bar, a plurality of toggle links connected to said bar and said compression members to cause said bar to move longitudinally when said compression members are moved transversely, a cover member, a longitudinal slot in said bar, and a stud securing said cover member to said back member, said stud passing through said longitudinal slot to stop the longitudinal movement of said bar before any of said toggle links reaches its dead center position.

3. In a loose leaf binder, a back member, a pair of compression members movable transversely of said back member, a bar connected to said compression members and movable longitudinally when said compression members are moved transversely, projections on said bar, a slide member secured to said back member, said slide member having an angularly disposed slot, and a pawl tooth mounted on said back member and projecting through said slot, sliding movement of said slide member causing said pawl tooth to move into and out of engagement with said projections to prevent or to permit outward transverse movement of said compression members.

4. In a loose leaf binder, a pair of cooperating sheet retaining members, a pair of compression members movable transversely relative to each other and adapted to exert pressure against said sheet retaining members to maintain them in said binder, a bar connected to said compression members so as to move longitudinally in one direction when said compression members move towards each other, and in the opposite direction when said compression members move apart, and means engageable with said bar to prevent movement of said bar in one direction.

5. In a loose leaf binder, a pair of cooperative sheet retaining members, a pair of compression members adapted to hold said sheet retaining members against the contents of the binder, and a flanged plate secured to each of said compression members to prevent accidental vertical or longitudinal movement of said sheet retaining members.

6. In a loose leaf binder, a back member, a pair of compression members movable transversely of said back member, a bar connected to said compression members and movable longitudinally when said compression members are moved transversely, a lever secured to said back member, means on said lever engageable with said bar to prevent expansion of said compression members temporarily, and means to permanently prevent movement of said lever when said first mentioned means is in position to prevent expansion of said compression members.

7. In a loose leaf binder, a back member, a pair of compression members movable transversely of said back member, a bar connected to said compression members so as to move longitudinally of said back member when said compression members are moved transversely, a plurality of teeth on one edge of said bar, a pawl tooth engageable with said teeth to prevent expansion of said compression members, and means to per-

manently lock said pawl tooth in engagement with said teeth, said permanent locking means permitting inward transverse movement of said compression members.

5. In a loose leaf binder, a back member, a pair of compression members movable transversely of said back member, a bar connected to said compression members so as to move longitudinally of said back member when said compression members are moved transversely, a slide member secured to said back member, means operable by said slide member engageable with said bar to prevent expansion of said compression members, a projection on said back member beyond the normal limit of travel of said slide member, means on said slide member engageable with said projection when said slide member is moved beyond its normal limit of travel to permanently prevent movement of said slide member.
10. 9. In a loose leaf binder, a back member, a pair of compression members movable transversely of said back member, a bar connected to said compression members so as to move longitudinally of said back member when said compression members are moved transversely, a plurality of projections on one edge of said bar, a pawl carrying a tooth engageable with said projections to temporarily prevent expansion of said compression members, a pivoted lever operable to move said pawl to engage and disengage said tooth from said projections, and an irremovable plug insertable into said binder to prevent movement of said lever when said tooth is engaged with said projections.
15. 10. In a loose leaf binder, a back member, a pair of compression members movable transversely relative to each other, a flanged plate secured to each of said compression members, and a pair of removable transfer bars carrying a plurality of sheet retaining prongs, the free ends of said prongs fitting under the top walls of said flanged plates when said binder is compressed to its minimum capacity.
20. 11. In a loose leaf binder, a pair of compression members slidably transversely relative to each other, a pair of removable transfer bars positioned adjacent said compression members, a plurality of sheet retaining prongs carried by said transfer bars, and a flange projecting inwardly from the side wall of each of said compression members, each of said flanges overlying one of said transfer bars and the free ends of the sheet retaining prongs carried by the other transfer bar when said binder is in its minimum capacity.
25. 12. In a loose leaf binder, a pair of compression members slidably transversely relative to each other, a pair of removable transfer bars positioned adjacent said compression members, a plurality of sheet retaining prongs carried by said transfer bars, and a flange projecting inwardly from the side wall of each of said compression members, each of said flanges overlying one of said transfer bars and the free ends of the sheet retaining prongs carried by the other transfer bar when said binder is in its minimum capacity.

PAUL O. UNGER. 35
